UNITED STATES PATENT OFFICE

MYRON H. SMITH, OF UTICA, NEW YORK

DESIGN FOR A COMBINED FIRE PUMP AND CONTAINER

Application filed July 10, 1930. Serial No. 36,316. Term of patent 14 years.

To all whom it may concern:

Be it known that I, MYRON H. SMITH, a citizen of the United States, residing at Utica, in the county of Oneida and State of New York, have invented a new, original, and ornamental Design for Combined Fire Pump and Container, of which the following is a specification, reference being had to the accompanying drawing, forming part thereof.

The figure is a perspective view of a combined fire pump and container showing my new design.

I claim:

The ornamental design for a combined fire pump and container as shown.

MYRON H. SMITH.
